UNITED STATES PATENT OFFICE.

MORRIS SAN, OF PASSAIC, NEW JERSEY, ASSIGNOR TO EAST JERSEY MATCH COMPANY,
OF GARFIELD, NEW JERSEY, A CORPORATION OF NEW JERSEY.

MACHINE FOR STRAIGHTENING MATCH-SPLINTS.

993.277

Specification of Letters Patent. Patented May 23, 1911.

Application filed March 2, 1910, Serial No. 546,813. Renewed February 4, 1911. Serial No. 606,643.

To all whom it may concern:

Be it known that I, MORRIS SAN, of Passaic, Passaic county, New Jersey, have invented a new and useful Improvement in Machines for Straightening Match-Splints, of which the following is a full, clear, and exact description.

My invention relates to improvements in
machines for straightening match splints
10 preparatory to dipping them in the paraffin
and firing compositions.

The object of my invention is to produce a simple and efficient machine which is adapted to straighten out a heap or pile of loose match splints so that they will be held in parallel relation and in a convenient tray, the latter being of special construction so that the splints will be held therein ready for insertion in the dipping machine. In practice I use a whole series of these trays which cover and form the bottom of the hopper, and which are constructed so that the splints which are in an essentially vertical position will drop through into another receptacle while the others will be straightened out in the trays.

Reference is to be had to the accompanying drawings forming a part of this specification, in which similar reference characters indicate corresponding parts in all the views.

Figure 1 is a side elevation of the machine embodying my invention. Fig. 2 is a plan view thereof. Fig. 3 is an end view of the machine. Fig. 4 is a plan view of one of the splint holding trays. Fig. 5 is a front elevation thereof, and Fig. 6 is a cross section of one of the trays.

The machine is provided with a suitable frame 10 at one end of which is mounted a driving shaft 11, and this communicates by means of eccentrics 12 and eccentric rods 13 with the yokes 14 which are connected with the arms 15 (see Fig. 1), and the latter are attached to the angle irons 16, two of which on opposite sides of the machine connect with a box or hopper 24 to be hereinafter referred to, while similar angle irons connect with the hopper at the rear end of the machine, as shown. The driving shaft is provided with a suitable pulley 17 to drive it, and a shifting lever 18 and shifter 19 are used for shifting the belt on the tight and loose pulleys 20 and 21 (see Fig. 2). All

this arrangement of the driving and shifting mechanism is only shown and described in a general way because obviously any other suitable mechanism for this purpose can be employed and there is no novelty claimed for that shown. 55
60

The angle irons 16 are provided with rollers 22 which run on the tops of the side frames 10, and the lower members of the angle irons 16 slide beneath keepers 23. It will thus be seen that a reciprocating motion will be imparted to the angle irons 16 and to the hopper 24 to which these angle irons are attached. This hopper is a rectangular box and is open at the bottom except for the longitudinal cross bar 25, while beneath it is a box 24^a to receive the splints which fall through during the straightening process. 65 70

When the straightener is to be used, the hopper is filled with trays 26, each of which is preferably formed of sheet metal, having closed ends 26^a, a closed back 27 and a closed bottom 28, except that an opening or slot 28^a is provided longitudinally in the bottom and next to the back, leaving the main portion of the bottom closed to support the splints which may lie thereon. The front of the tray is open and the tray is provided with numerous transverse partitions 29 the full height of the tray, these partitions being spaced apart so that the distance between them is less than the length of a match. The partitions 29 are attached to the bottom only so as to leave the slot 28^a unobstructed. When the machine is to be used, the hopper is filled with these trays which are arranged with their ends resting on the ledges 24^a at the sides of the hopper (see Fig. 2) and the cross bar 25 in the middle, the hopper being entirely filled, that is having its bottom entirely covered with these trays. In Fig. 2, however, I have shown but four trays in position, but it will be understood that they can be extended so as to fill the hopper bottom. The trays being placed in position, the loose splints are filled into the hopper 24 and the machine set in motion, which causes the hopper to be shaken backward and forward through the driving mechanism already described. As the shaking takes place, the splints which are essentially vertical, will fall down through the openings 28^a, while those which

are at an angle to a vertical plane will enter between the partitions 29 and gradually be straightened out between the partitions, so that in a short time the loose splints will 5 have fallen down through the openings 28^a, while the remaining splints will fill the trays and lie straight. It will be observed that the partitions 29 project from the front of the box or tray so that when the several 10 trays are in position there will be openings between the bottom of one tray and the back of the next tray corresponding to the slot 28^a already referred to so that space is provided for the vertical splints and pieces to 15 fall through both the slot 28^a and the space left between the front pieces of the partitions 29, and the splints are then ready for insertion in the dipping machine. The 20 splints which fall through the openings 28^a are gathered up and thrown into the hopper again, when a new set of trays are in position.

It will be seen that the machine is very 25 simple and that the splints can be very nicely straightened and easily handled.

Having thus fully described my inven-

tion, I claim as new and desire to secure by Letters Patent:—

1. An apparatus of the kind described, comprising a reciprocating hopper and a 30 series of removable trays forming the hopper bottom, each tray being provided with an open front portion, transverse straightening partitions, and an opening through the bottom for the passage of splints. 35

2. An apparatus of the kind described, comprising a reciprocating hopper having a longitudinal cross-bar in the center and supporting ledges at the sides, in combination with straightening trays carried on said 40 ledges and cross bar.

3. In an apparatus of the kind described, the straightening trays closed at the sides and backs and open in front, said trays having transverse straightening partitions 45 therein, and a longitudinal opening in the bottom thereof.

MORRIS SAN.
